UNITED STATES PATENT OFFICE.

CHARLES H. FERGUSON AND ALFRED BAKER, OF BOSTON, MASSACHUSETTS.

COAL AND ASH SIFTER.

SPECIFICATION forming part of Letters Patent No. 289,820, dated December 11, 1883,

Application filed March 29, 1883. (No model.)

To all whom it may concern:

Be it known that we, CHARLES H. FERGUSON and ALFRED BAKER, both citizens of the United States, residing at Boston, in the county 5 of Suffolk and State of Massachusetts, have invented a new and useful Coal and Ash Sifter, of which the following is a specification, reference being had to the accompanying drawings.

10 Our invention relates to sifters for sifting coal and ashes; and it consists in the several parts, constructed, arranged, and combined as hereinafter set forth, and specifically pointed out in the claims.

15 In the drawings, Figure 1 is a side elevation of a coal and ash sifter embodying our invention. Fig. 2 is a vertical section taken on line 1 1 in Fig. 1. Fig. 3 is a vertical section taken on line 2 2 in Fig. 2.

20 The box containing the working parts consists of the upper part, A, and lower part, B, the former being hinged to the latter at *a*. The part A is formed by the sides *b b*, ends *c* and *d*, and top *e*, the part B by the sides *f f* 25 and ends *g* and *h*. In the upper part, A, is a sieve in the form of a barrel or drum, C, tapering, as shown, and formed of woven wire properly stayed, or of suitable perforated material. This barrel is set inclined, and has a 30 flange, *i*, at its upper and larger end, which fits to revolve in a suitable bearing formed about an opening in the end *c*. There is a shaft, D, attached to the lower and smaller end of the barrel C, which is fitted to revolve 35 in a bearing in the end *d*. The inner end of the shaft D is connected to the barrel by means of a disk, E, and rods *j*, which join the disk and the barrel and act as stays for the latter. Thus the barrel C is supported by means of 40 the bearings in the ends *c* and *d*. There is an open space between the disk E and the small end of the barrel, as shown.

In the part B of the box is a sieve, F, in the form of a spout, made of woven wire or suitable perforated material. This sieve is set inclined, as shown, pivoted at its upper edge on a rod, *k*, and open at the top *l*. The lower end extends into or through a suitable opening in the end *g*.

50 In the shaft D is a crank, G, to be turned

by hand, and a shorter crank, *m*. Pivoted on the crank *m* is one end of a connecting-rod, H, which is pivoted at the other end to a rod or bar, I. This bar is pivoted, midway its length, on a rod, J, and at its inner end to the 55 bottom of the sieve F at *n*.

Fastened on the end *c* of the upper part of the box is a hopper, K, to receive the coal and ashes to be sifted. This hopper is so formed as to have a flange, *o*, which extends a suitable distance into the barrel C, so as to guide the coal and ashes into the barrel. There is a cover, L, for the hopper K, hinged at *p* to the top *e*. There is a hook, *q*, at each side of the box, fixed to and pivoted by means of a transverse rod, *r*. These hooks hook into notched pieces *s*, so that the part A of the box may be fastened down on the part B or held at different inclinations relative thereto, whereby the barrel C is held at any desired inclination. 60

For operation, the sifter is placed over a suitable place of deposit for the ashes, and the coal and ashes to be sifted are put into the hopper K. On turning the crank G the barrel C is revolved and the sieve F vibrated. The 65 coal passes through the barrel C, falls into the sieve F at *l*, and passes out at the lower end thereof. The ashes fall through the openings in the sides and bottom of the barrel C and sides and bottom of the sieve F, and through 70 the open bottom of the box. A shield, M, is fixed between the barrel C and the sieve F. This shield is of such shape and is so located that the ashes falling from the barrel C will not drop onto the sieve F, but will be so directed as to fall between the sieve F and the 75 sides of the box. 80

We claim as our invention—

1. The combination of the sieve C, tapering and inclined, the smaller end being lower than 85 the larger end, and means for revolving the same, with the sieve F, pivoted as at *k*, and means whereby it may be vibrated, substantially as set forth.

2. The combination of the tapering sieve C, 90 having flange *i* at its larger end, the box A B, having bearings for flange *i* and shaft D, the shaft D, having crank *m*, the pivoted bar I, and the pivoted sieve F, substantially as specified.

3. The combination of sieve C, sieve F, shaft D, crank *m*, connecting-rod H, and pivoted bar I, substantially as set forth.
4. The combination of the hopper K, sieve C, tapering and inclined, the smaller end being lower than the larger end, means for revolving sieve C, sieve F, means for vibrating the same, and shield M, substantially as specified.
- 10 5. The herein-described coal and ash sifter, comprising the box formed of the parts A and B, the part A being hinged to the part B, and

having a bearing in the end *c* for a flange, *i*, at the larger end of a sieve, C, and a bearing in the end *d* for a shaft, D, connected with the 15 smaller end of said sieve, the hopper K, rotary sieve C, sieve F, and means for vibrating the sieve F, substantially as specified.

CHARLES H. FERGUSON.
ALFRED BAKER.
